UNITED STATES PATENT OFFICE.

PAUL BUTLER, OF LOWELL, MASSACHUSETTS.

CARTRIDGE-SHELL.

SPECIFICATION forming part of Letters Patent No. 364,213, dated June 7, 1887.

Application filed May 28, 1885. Serial No. 166,903. (No model.)

To all whom it may concern:

Be it known that I, PAUL BUTLER, of Lowell, in the county of Middlesex and State of Massachusetts, have invented a new and useful Improvement in Cartridge-Shells, of which the following is a specification.

My invention relates to metallic cartridge-shells; and it consists in preparing the paper or other fibrous re-enforce of such shells with some composition in the nature of a filling material and inserting it into the shell under conditions which will cause it to fit to the metal of the shell with the effect and substantially as hereinafter described and claimed.

15 In the drawings, Figure 1 is a rear end view of a metallic cartridge-shell. Fig. 2 is a side view of the same, partly in section, showing the re-enforce.

A is the metallic shell, and B is the re-enforce formed of paper or some similar fibrous material. The shell is stamped and drawn from soft metal in the usual manner, and the re-enforce is inserted in any usual and well-known manner. When the paper re-enforce 20 is made in the usual way by stamping or pressing out the paper, however, it is found practically impossible to draw the shell down below a certain degree of thinness, because the amount of moisture contained in the paper under ordinary atmospheric conditions causes the re-enforce to shrink away from the metal of the shell slightly at the line b of the seam between them. This allows the gases created by the explosion of the powder to enter the seam between the re-enforce and the metal of the shell all around, or in some parts of it around the line b, and to exert great force upon the metal at this point, and to frequently so burst or strain it as to render the

40 shell incapable of being reloaded and used repeatedly, unless the metal is left of sufficient thickness to resist this strain. If the metal be made thicker at this point or line and from it toward the head of the cartridge-shell, and 45 thinner from any point or place toward the open end of it, to save metal, the unequal resistance of the different thicknesses of metal will cause the force of the explosion to burst the shell at the junction of such thick and 50 thin portions. Thus the thickness of the shell

at the line b practically regulates its thickness elsewhere in its cylinder. It is to overcome these difficulties and enable the shells to be made thinner and effect a saving of metal in them, while retaining sufficient strength for 55 use, as described, that my invention is made.

Before inserting the re-enforce B in the metallic shell I soak the same in some substance or composition which will expel the moisture from it, and fill its pores and fibers, 60 so as to preserve its proper elasticity and prevent its shrinking away from the metal, as described, and which will also remain in the re-enforce under the ordinary conditions of heat and exposure to which such shells are 65 subject, and not be absorbed therefrom into the powder by capillary attraction or absorption, and so destroy the explosive properties of the powder. For this purpose I have found stearine, or Japan wax, or beeswax, or 70 other similar wax, or a compound of wax and tallow, or wax and similar substances in which no free oleine exists, quite sufficient. The proportions of wax and tallow may be somewhat varied, according to the density of the 75 paper and length of time which it is soaked therein; but I have found one-fourth part of tallow and three-fourths parts wax melted together to be efficient, and a soaking of fifteen or twenty minutes for paper of the density 80 commonly used.

In all cases where tallow or any lubricant containing oleine is used as an ingredient care must be used to not employ a sufficient proportion of the same in the mixture to have 85 the oleine escaping from the re-enforce and causing shrinkage of the same and injury to the powder under subsequent keeping of the loaded shell.

Any other similar substances to the above- 90 described mixture of wax and tallow, or mixtures thereof, may be used—such as gums or resins—which will accomplish the result desired—i. e., remain in the re-enforce and be elastic and non-shrinkable.

It may be found expedient to warm or heat the re-enforce after being soaked in the waterproofing elastic substance or compound, as above described; but I have found the heat generated by the punch in stamping the re- 95 100

enforce into place in the shell amply sufficient to seat the re-enforce in place and cause it to adhere to the metal of the shell in most cases.

What I claim as new and of my invention

5 is—

The combination of the metal shell A with the elastic non-shrinkable re-enforce B, formed of paper saturated with the moisture-proof elastic substance, or mixture non-absorbent

therefrom, and fixed in the bottom and firmly 10 against the outer cylindrical wall of the chamber of the shell by pressure, substantially as described.

PAUL BUTLER.
